[57] **CLAIM**

The ornamental design for a multi-purpose vehicle, as shown and described.

DESCRIPTION

FIG. 1 is an isometric view of a multi-purpose vehicle showing our new design;

FIG. 2 is a side elevation view thereof, the opposite side being a mirror image of that shown;

FIG. 3 is a top plan view thereof;

FIG. 4 is an enlarged rear elevation view thereof;

FIG. 5 is an enlarged front elevation view thereof;

FIG. 6 is an isometric view of a multi-purpose vehicle showing a second embodiment of our new design;

FIG. 7 is a side elevation view of FIG. 6, the opposite side being a mirror image of that shown;

FIG. 8 is a top plan view of FIG. 6;

FIG. 9 is an enlarged rear elevation view of FIG. 6; and

FIG. 10 is an enlarged front elevation view of FIG. 6.
